UNITED STATES PATENT OFFICE.

ROBERT H. KEATON, OF SAN FRANCISCO, CALIFORNIA.

GUN.

1,335,342.

Specification of Letters Patent. Patented Mar. 30, 1920.

Application filed July 12, 1918. Serial No. 244,524.

To all whom it may concern:

Be it known that I, ROBERT H. KEATON, a citizen of the United States, residing at the city and county of San Francisco and State 5 of California, have invented new and useful Improvement in Guns, of which the following is a specification.

This invention relates to a gun, and particularly pertains to a gun of the mechanically-operated type.

In present day warfare it has been found desirable to produce impelling means for projectiles other than explosives. In solving the problems incident thereto it is necessary to provide a structure which may be readily operated mechanically and which lends itself to fire the projectiles at rapid speed and with certainty of aim. It is the principal object of the present invention to 15 provide means for accomplishing these results.

Another object of the present invention is to provide a feed mechanism operating in synchronism with the throwing member to 25 deliver projectiles to the barrel and to insure that they will be thrown therefrom without jamming in the feed mechanism or the barrel.

The present invention contemplates the 30 use of a barrel of any desired caliber mounted upon a base, from which it may be swung either horizontally or vertically, said base at the same time carrying a positively operated projectile feeding mechanism 35 which delivers the projectiles to the barrel from which they are thrown by the action of a rotary projector.

The invention is illustrated by way of example in the accompanying drawings, in 40 which—

Figure 1 is a view in elevation disclosing the operating mechanism, and particularly disclosing its pivotal connection.

Fig. 2 is a fragmentary view in section 45 and elevation illustrating the means provided for tilting the gun vertically.

Fig. 3 is a fragmentary view in plan illustrating a portion of the feed mechanism provided for the projectiles.

Fig. 4 is a view in section and elevation 50 disclosing the manner in which the projectiles are delivered from their hopper to the feed conveyer.

Figs. 5 and 6 illustrate the manner of delivering the projectiles from the feed mechanism to the barrel of the gun.

Fig. 7 is a view in side elevation illustrating the gun barrel, the feed hopper, the projector and the mounting for said members.

Fig. 8 is a view in plan further illustrating the parts disclosed in Fig. 7 and the relation between the gun mounting and its barrel.

Fig. 9 is a fragmentary view in vertical section illustrating the lower portion of the feed hopper.

Figs. 10 and 11 are views in elevation and plan, respectively, illustrating the manner in which projectiles may be delivered to the barrel by a conveyer belt.

Fig. 12 is a view in section showing the formation of the guide way provided for the projectiles as they pass to the feed mechanism.

Fig. 13 is a view in side elevation illustrating another form of the gun, and particularly the carriage construction.

Referring more particularly to the drawings, 10 indicates a base member which is formed as a portion of a motor cage 11. 80 This motor, as will be understood, may be of any desired type, and in the present instance is illustrated as an electric motor disposed with its armature shaft standing vertical. Formed as a portion of the motor casing at its upper end are bearing lugs 12. A pair of these lugs is provided to carry a worm shaft 13, upon which a worm gear 14 is secured. The shaft is provided with a hand wheel 15 or other suitable means by which 85 it may be easily operated. The worm gear 14 is in constant mesh with a worm wheel 16. This wheel is disposed horizontally and circumscribes the vertical axis of the motor. The worm wheel is rotatably mounted upon 90 an upstanding hub 16', preferably cast integral with the motor housing.

The worm mechanism is provided as a means for horizontally rotating a gun frame 17. This frame is particularly shown 100 in Fig. 1, where it will be seen to comprise upper and lower halves 18 and 19. The lower half has a central, vertical bore by which it is rotatably mounted for horizontal movement upon the upwardly extending 105 hub of the motor case. The two halves are

united along a horizontal line and are formed with bearing portions which, when combined, provide suitable support for a horizontal drive shaft 20. This shaft is 5 driven by the motor by means of a driving pinion 21 which is in constant mesh with a driving gear 22. The gear 22 is fixed to the upper end of the motor shaft 23 and is partially surrounded by the lower portion 10 of the frame.

The rotary action of the motor and these bevel gears will continuously rotate the shaft to drive a projector blade 24 and a projectile feed member 25. Due to the eccentric disposition of the projector blade 24 15 the shaft is provided with a counterbalancing member 20', secured on the end of the shaft adjacent to the blade.

The feed member 25 is here shown as a 20 continuous worm which forms a feed groove into which the projectiles are delivered from a feed hopper 26. This hopper is directly disposed in front of the feed member 25 and is provided with a false bottom wall 25 27. This wall is adapted to rotate upon a shaft 27' and is formed with peripheral teeth engaging the teeth of the feed member 25. The floor 27 is formed with a series 30 of depressions 28 which are arranged in spaced relation to each other along the upper face of the floor and near the outer edge thereof. These depressions are also in concentric relation to the axis of the floor and are in the proper relation to the feed member 25 to insure that a projectile will be carried into the feed groove of said member as the two members rotate in unison. A guide plate 29 is secured to the side wall of the hopper and extends over the movable 40 floor thereof. This plate is not entirely concentrically arranged in relation to the axis of the hopper, but extends outwardly and directs the travel of the projectiles from the depressions on the rotatable floor into 45 the groove of the feed member. As particularly shown in Fig. 4, the main body of this plate is angular and forms an inclosing shield for the projectiles so that they will not jam in the feed member and will be delivered thereto, as determined by the spacing of the depressions upon the plate 27. The formation of this guide plate at its forward end is shown in Fig. 12, while the lateral retaining portion is shown in Fig. 6.

55 The hopper 26 is carried by an angular arm 30. This arm is pivotally mounted upon the shaft 20 and extends forwardly and then parallel in relation to the axis of this shaft. The outer end of the arm is provided with supporting and clamping means 60 for a gun barrel 31. The barrel may be of any desired caliber and must be formed with a longitudinally extending slot 31'. This slot passes vertically through the central axis of the barrel and is of sufficient

width to allow free passage of the projector blade therethrough, at the same time leaving a portion of the bore of the gun unimpaired. This will provide a run-way for projectiles as they are forced forwardly by the projector. The rear end of the gun barrel terminates substantially against the circumference of the feed member 25 and in direct communication with the end of the feed groove thereon. The projectiles when delivered along this groove will pass to a point in alignment with the path of travel of the swinging impeller and will at this point pass into the gun barrel, as particularly shown in Fig. 5, after which the impeller will force the projectile forwardly and cause it to pass out of the opposite end of the muzzle.

In order that the gun barrel may be swung vertically the bracket member 30 is fitted with a gear segment 32 which is secured to the bearing portion of the bracket and is in engagement with a worm gear 33 rotatably held by the upper frame member of the gun. This gear is rotated by a hand wheel 34 and will swing the gear segment 32 and its angular bracket 30 through a vertical plane. Thus it will be seen that the combined manipulation of the hand wheels 15 and 34 will permit the gun barrel to be aimed at any point.

In the gun construction as disclosed and described in the preceding part of the specification the use of spherical projectiles has been contemplated. These members may be 100 solid metal balls or may be formed as containers for explosives. In case, however, that other forms of projectiles are to be used in the gun, it may be desirable to provide other feed and conveyer means. In Figs. 10 105 and 11 a cylindrical projectile 35 is used and is delivered to the gun barrel by means of a conveyer belt 36. This belt passes over suitable pulleys 37 and carries a series of cleats 38 adapted to consecutively pass beneath a 110 gravity feed hopper 39. As the cleats pass beneath this hopper they will carry one of the projectiles and will deliver it to an inclined run-way 40 which will convey it to the gun barrel. This type of projectiles may be 115 used embodying a fulminate explosive cap. As the cap is placed upon the forward end of the projectile the force of the projector will not cause a premature explosion to be made. It will be readily recognized that 120 bombs of various design can be thrown with this machine without danger to the operator and with accuracy of fire.

It will be evident that various changes 125 and modifications may be made in the construction of the gun, and particularly in the manner in which it is driven and mounted. Another form of construction is shown in Fig. 13, where it will be seen that a rigid base plate 41 is provided, and may be se- 130

cured to a permanent gun mount. This plate has an upwardly extending hub adapted to receive a pivot pin 42. The pin 42 stands vertically, and is formed as a part of 5 a turn-table 43. This table is adapted to swing horizontally, due to the rotary support of the pin within the base, and is formed with a series of gear teeth 44 around its edge, which are in mesh with an operating pinion 45. The pinion 45 is fixed to a hand-wheel shaft 47, at the upper end of which a hand wheel 48 is secured. The shaft 47 may be rotatably held in a bearing bracket 49 carried by the base 41. Rotation 10 of the gear 45 will produce a rotation of the turn-table 43 and swing the entire gun mechanism horizontally. The turn-table 43 carries an operating motor 50, the shaft of which is provided with a driving gear 51. 15 This gear is in constant mesh with a pinion 52 secured to the end of the shaft 20. It will be understood that this is the shaft upon which the projector blade 24 is mounted and by which it is driven. The shaft 20 in the 20 present construction is carried in opposite bearings forming a part of the frame member 53 corresponding to the frame structure 17 in the previous design. The frame 53, however, is fixed to the turn-table 43 by 25 standards 54. The shaft 20 is provided with an arm 30 by which the gun barrel is carried. This arm is of the construction previously described, and may be swung vertically upon the axis of the shaft by means of 30 the gears 32 and 33.

In the operation of the gun first described, a suitable rigid gun mount is first provided, after which the base portion 10 is secured to this mount. The aim of the gun may then be 40 controlled by manipulation of the two hand wheels 15 and 34 and the fire thereafter produced by the rotation of the projector as driven by the motor 11. This projector is formed with a peripheral surface, a portion 45 of which is concentric to its rotating axis and the remainder of which is eccentric thereto. Due to this construction of the blade the projectiles are taken from the feed mechanism in substantially a state of rest 50 and are thereafter engaged by the driving edge of the projector to cause them to gradually increase their speed as the projector rotates. It will be understood that by the time the projectile has reached the point *a* 55 of the projector it will have attained a sufficient speed to travel at a predetermined velocity.

During the movement of the projector the projectiles will first encounter the concentric 60 surface *b* and will thereafter be forced along the eccentric face *c* to the top *a*. The delivery of the projectiles to this eccentric surface and the barrel muzzle will, of course, be effected by the continuous operation of 65 the shaft 20 as it simultaneously drives the

impeller blade and the delivery screw 25. This last-named member is in mesh with teeth upon the periphery of the rotating floor 27 of the feed hopper and thus automatically furnishes itself with projectiles 70 which it afterward empties into the barrel of the gun.

The operation of the blade 24 will be identical in both of the structures shown in Figs. 1 and 13. In the latter design the 75 manipulation of the carriage to aim the gun will, however, be slightly different. Horizontal swinging movement of the barrel is effected by rotating the turn-table 43 as well as the motor, while vertical swinging movement is produced by rotation on the hand wheel 15 as previously described.

It will be readily recognized therefore that the feeding and firing of the gun is in absolute synchronism and that under the 85 present arrangement one projectile will be delivered to the barrel upon each revolution of the shaft 20. It will be understood that variation in the timing of the feed in relation to the revolution of the shaft may be 90 effected by closing certain of the recesses 28 in the rotating floor 27 of the hopper. Thus the projectiles may be fired in succession and at any desired interval in relation to each other, the conical plate 25' serving to 95 continuously direct the projectiles downwardly toward the recessed surface of the floor 27, and thus insuring that these recesses will at all times be supplied with the balls.

In the form of the feed device shown in 100 Figs. 10 and 11, the hopper 39 may be filled, and as the conveyer belt rotates in the direction of the arrow *a* the cleats 38 will successively carry the projectiles to the barrel. The firing operation would be the same with 105 either type of feed.

It will thus be seen that by the use of a gun of the present construction a large number of projectiles of any desired shape may 110 be successively thrown or fired as directed by a gun barrel and may be readily drawn from a hopper which does not require skill in its feeding nor skill in the operation or manipulation of the main mechanism of the gun.

While I have shown the preferred form of my invention as now known to me, I wish it understood that various changes in the construction, combination and arrangement of parts may be made by those skilled 115 in the art without departing from the spirit of my invention as claimed.

In the event that the motor driving the gun mechanism is not self-governing it may 120 become necessary to apply some sort of governor mechanism to insure that the projector blade will rotate at a constant rate of speed, and will, therefore, fire the projectiles at uniform velocities.

Having thus described my invention, what 130

I claim and desire to secure by Letters Patent is—

1. A catapult gun comprising a guiding barrel, a device for feeding projectiles, an impeller, and a spirally grooved worm by which projectiles are transferred into the line of movement of the impeller.
2. An apparatus comprising a directing gun barrel, a feed hopper and an impeller acting in line with the barrel, a spirally channeled worm by which the projectiles are carried into the path of the impeller, and a rotatable floor having depressions around the upper face thereof and co-acting with the channels of the feed worm.
3. An apparatus comprising a directing gun barrel, a feed hopper and an impeller acting in line with the barrel, a spirally channeled worm by which the projectiles are carried into the path of the impeller, a rotatable floor having depressions around the

upper face thereof and co-acting with the channels of the feed worm, and a guide plate fixed with relation to the rotatable floor and the feed worm grooves.

4. In a gun of the character described, a hopper, an impeller, a gun barrel to receive projectiles from the hopper and the revolute impeller, the gun barrel having means to change its direction vertically and horizontally, a motor and gearing driven thereby, a spirally grooved carrier, and a co-acting guide to insure the passage of the projectiles from the hopper to the path of the impeller and into the barrel.

In testimony whereof I have hereunto set my hand in the presence of two subscribing witnesses.

ROBERT H. KEATON.
